UNITED STATES PATENT OFFICE.

JOHN A. YORK, OF FRANKLIN, CONNECTICUT.

INDICATING SWITCH-BUTTON.

972,048.

Specification of Letters Patent. Patented Oct. 4, 1910.

Application filed February 17, 1909. Serial No. 478,459.

To all whom it may concern:

Be it known that I, JOHN A. YORK, a citizen of the United States, and a resident of Franklin, in the county of New London 5 and State of Connecticut, (whose post-office address is North Franklin, Connecticut,) have invented a certain new and useful Indicating Switch-Button, of which the following is a full, clear, and exact description, whereby any one skilled in the art may 10 make and use the same.

The invention relates to indicators for switches. That is, a device which will visually show the position of the switch parts 15 and show at a glance whether said parts are in closed or open circuit position.

It relates more particularly to a turn or thumb button for actuating an electric switch, which not only serves as a means 20 for operating the switch, but also has embodied therein an indicator automatically actuated to show the position of the switch parts when the switch button or operating means has been utilized to move the parts 25 of the switch mechanism.

The objects of the invention are to provide for a certain and accurate indication of the position of the switch mechanism.

A further object is to provide an indicating mechanism applied to the switch handle or button.

A further object is to provide an indicating button or switch handle having an indicating device and also means for readily attaching and detaching the button and indicating device from the switch mechanism, at the same time providing a predetermined 35 position of attachment of the switch button or handle with reference to the switch mechanism.

In the accompanying drawings Figure 1 denotes a plan view of an ordinary rotary snap switch with the cover removed, a type of electrical device well-known in the art 45 for making and breaking an electric circuit. Fig. 2 illustrates the switch mechanism shown in Fig. 1 in partial vertical section with the improved indicating switch button applied thereto. Fig. 3 is an enlarged sectional view of the switch button 50 and appurtenant parts showing the indicator in the normal position. Fig. 4 is a similar view of the indicating mechanism illustrating the indicator in the position occupied after a movement of the button or

handle and corresponding movement of the switch parts. Fig. 5 is a plan view of the button or handle showing the indicator opening. Fig. 6 is a developed plan view of the housing of the indicator. Fig. 7 is a side view showing the housing plate of Fig. 6 partially bent to the form of the housing. Fig. 8 is a top plan view of the housing with the parts bent into place. Fig. 9 illustrates in perspective the housing, indicator dial and operating mechanism unassembled. In this figure, 9^a shows the complete housing. 9^b shows the indicator dial with one of the pivots broken away to illustrate the toggle connection with the operating yoke. 9^c illustrates the operating yoke. 9^d illustrates the actuating ring for reciprocating the actuating yoke. 9^e illustrates the clutch member of the switch mechanism which interengages with the actuating ring and cooperates therewith to connect the mechanisms of the switch button and switch. Fig. 10 is a rear face view of a flush plate illustrating the lugs for reciprocating the actuating ring and appurtenant parts. Fig. 11 is a sectional view through the plate illustrated in Fig. 10 showing the alternately raised and depressed actuating lugs. Fig. 12 is a cross-sectional view in detail through the threaded nipple and spindle. Fig. 13 is a perspective view with parts broken away illustrating the top of the cap or cover and lugs which cooperate with the actuating mechanism for the indicator.

In switch mechanism, particularly those of the rotary snap switch type, it has been found desirable to inclose the switch mechanism with as nearly as possible a dust-proof cover. When so inclosed, it is essential that the position of the switch parts be indicated so that the operator may know whether the circuit controlled by said switch is "opened" or "closed".

It has been common practice to provide a sight opening through the cover and arrange a dial which will rotate with the switch parts and indicate through the sight opening whether the circuit is opened or closed. In many instances, such dials are attached to the cover whereby they are removable and leave the various switch parts entirely uncovered and unobstructed, or they have been removably secured to the switch parts and connected with the switch button or handle in such manner that the handle

might be removed and upon the removal of the cover, the switch dial or indicator could be taken out.

In devices of this type employing a switch 5 button or handle, it has been found necessary to provide some form of spring connection, between the switch button and switch spindle, in order that the button would automatically take up inequalities and always 10 fit closely against the switch cover, thereby holding the parts in place, preventing loose connections.

In the present invention, the various features of indicating the position of the switch 15 parts and securing the necessary spring connection between the button and switch parts have been coalesced into the switch button or handle itself. Thus, said button has all the inherent features of advantage, which 20 have heretofore existed only, by combining various elements including a button with a spring connection and a removable dial co-operating therewith and either attached to the switch cover or removably attached to 25 the switch parts.

The switch forms no part of the present invention, as obviously, the improved indicating button or handle may be adapted to various forms of mechanism and said mechanism is therefore only briefly described herein.

Referring to Figs. 1 and 2, the numeral 1, denotes a switch base of insulating material upon which are mounted stationary contacts 30 2, 3, provided with means for attaching line-wires thereto. The circuit terminating in the stationary contacts 2, 3, is opened or closed by the rotation of a switch bar 4, suitably mounted upon an actuating spindle 35 5, and provided with locking and releasing mechanisms through which a rotation of the spindle 5, will cause a quick step-by-step movement of the contact bar 4, and make or break the circuit as the bar 4, engages the 40 stationary contacts 2, and 3, (as illustrated in full lines in Fig. 1,) or occupies a position as illustrated in dotted outline in said figure.

Suitably positioned upon the spindle 5, is a threaded nipple 6, which is non-rotative 50 with respect to the spindle 5, but has a slight axial movement thereon. This nipple is ordinarily held at the lower limit of its play by a spring 7, which is located intermediate the nipple and the head of the spindle. The 55 nipple 6, is threaded to engage a co-operating thread 8, formed in the housing 9, of the switch button or handle and when said parts are screwed together, the handle is brought firmly, though resiliently, into engagement 60 with the switch cover, the spring 7, providing the necessary tension to permit the parts to properly adjust themselves as the button or handle is screwed down.

Surrounding the nipple and the end of the 65 housing is a two-armed clutch member 10.

This is secured to the switch parts in predetermined position and forms one part of a clutch between the switch button and rotary switch mechanism. As illustrated herein, the clutch part 10, is formed to engage openings 11, 12, of an actuating ring 13, and prevent rotation of said ring 13, with respect to the switch button and switch mechanism, except at such periods as the switch mechanism is released to make its engaging or disengaging movement. The actuating ring 13, within reasonable limits is free to reciprocate axially of the spindle and clutch member 10, and this axial movement of the ring 13, as hereinafter described, controls the 80 movement and position of the indicator.

The switch button 14, is preferably formed of a suitable insulating material which may be molded, cast, or otherwise formed to inclose the housing and indicator parts. It is 85 provided with a central sight opening 15, through which the indicator may be observed. The lower end of the button is preferably recessed as at 16, to provide space for the actuating ring 13, and is so formed that 90 it comes into close contact with the cover 17, of the switch.

Within the button 14, suitably secured as by molding or otherwise forming said button, is a housing 9, which in practice is preferably formed by stamping or blanking out a piece of metal, as illustrated in Fig. 6, providing co-operating lugs 18, 19, which, when bent to form, as illustrated in Figs. 7, 8, and 9, provide a tubular shank 20, which may be 100 suitably threaded to engage a threaded nipple 6. A pair of tangs or lugs 21, 22, are also provided, which, when bent to form, as illustrated in Figs. 7, 8 and 9 form two sides of the housing 9. As the metal is blanked 105 out, a sight opening 23, is formed centrally thereof, and pivot openings 24, 25, are provided on opposite sides of said opening 23, in such position as to form a bearing for the indicator blade when the housing is formed 110 to shape such as illustrated in Fig. 9.

Pivots mounted in the housing 9, is an indicator blade 26, of somewhat peculiar form having pivot lugs 27, which have a bearing in the pivot openings 24, 25. Concentrically arranged with reference to the pivot lugs 27, is a blade 28, bearing suitable indications which may be observed through the sight opening 23, of the housing 9, and the opening 15, of the button. These indications may be made by having a portion of the blade 28, of a light color followed by a dark color, or the words "off" and "on" might be printed thereon.

The pivoted member 26, has the indicating portion 28, concentrically formed with reference to the pivots 27, and as the housing 9, is also curved to correspond to the curvature of the indicator plate, a close running fit is provided between the indicator plate 130

and housing and this insures a tight dust-proof arrangement, although the sight opening 15, is, of course, always open. At one side of the pivots 27, there is a lug 29, which engages a recess 30, of corresponding form in an actuating yoke 31. This yoke 31, passes through a slot or opening 32, in the upwardly extending portion of the indicator plate and forms a convenient means for tilting said indicator plate upon its pivots, whenever it is raised or lowered by an actuating ring 13.

The actuating yoke 31, is provided at the lower end of its two arms with openings 34, 35, which form a floating bearing for the actuating ring 13. In assembling the parts, the actuating yoke is sprung slightly until its two arms pass through the opening of the actuating ring 13, and when released, spring outward with the notches 34, 35, engaging the inner edges of the ring 13. The opening through the ring 13, is of a suitable size to fit freely over the threaded shank of the housing and as the arms of the actuating yoke project through the slotted openings of the shank, the actuating ring and various parts when assembled, form a most compact and simple structure which will give absolute certainty of action with reference to the indicating plate.

36. When the various parts above described have been fully assembled in the switch button, said button may be attached to the switch mechanism by simply screwing the threaded shank of the housing over the threaded nipple 6. As the button is screwed down, the openings 11, and 12, of the actuating ring come into engagement with the arms of the clutch member 10, and thereupon the actuating ring is held against rotation.

40. Normally, the ring 12, rests upon the upper surface of the cover 17. This cover has a central opening through which the spindle passes and about said opening are arranged lugs adapted to engage the floating ring and depress it or raise it as the switch mechanism is rotated. As shown herein, the actuating ring 13, is provided with a pair of projecting lugs 36, 37, arranged in the same axial line. The cover is also provided with 45 a pair of lugs projecting above the surface of the cover and a pair of lugs projecting below the surface of the cover. These lugs are arranged in pairs diametrically opposite each other and in such position that upon 50 rotation of the switch mechanism, the lugs 36, 37, of the actuating ring will first be brought into engagement with the upwardly extending lugs of the cover and said lugs having an inclined surface, the ring 13, will 55 be depressed passing below the cover under the lugs. This downward movement of the ring depresses the actuating yoke 31, which 60 through its connection with the lug 29, swings the indicator 26, and thus moves the 65 indicator plate 28, with respect to the sight

opening 15. A further movement of the switch parts brings the lugs 36, 37, of the actuating ring 13, into contact with the inclined surfaces of the downwardly projecting lugs of the cover, and thereupon the ring 13, is forced upward through the cover opening raising the actuating yoke 31, and correspondingly moving the indicator plate 28.

It will be observed that all of the various parts are loosely connected so that there is 75 practically no chance of cramping or binding and yet the vertical movements of the actuating ring 13, will be positively transmitted to the indicator 26, always moving it in predetermined manner.

80. As the clutch member 10, is positively positioned on the switch mechanism with reference to the rotating switch blade 4, it is obvious that the ring 13, through its notches 11 and 12, must always engage the clutch member 10, in a predetermined manner and as the ring 13, floats with reference to the actuating yoke, the button may be screwed down without interfering with the engagement of the clutch member 10, and 85 actuating ring. The ring 13, being held against rotation by the clutch member 10, can only rotate when the switch parts move and during said movement is depressed or raised as its lugs 36, 37, engage the inclined 90 surfaces of one or the other of the pairs of lugs of the cover.

95. In Figs. 10 and 11, there is shown a form of cover such as is employed in flush switches. This plate, of course, rests against the wall, covering the opening in which the switch box and switch mechanism are arranged. It has a central opening 50, substantially the same as the opening through 100 an ordinary switch cover and with the depressing and raising lugs arranged identically as described above. Two of these lugs 51, 52, project below the surface of the plate and the other two lugs 53, 54, project on the opposite side of the plate. It is obvious 105 that upon rotation of the ring 13, its lugs 36, 37, when engaging the lugs 51, 52, will force the ring through the plate in one direction and when engaging the lugs 53, 54, the ring will be forced through the plate 110 in the opposite direction.

115. The improved switch button is particularly well adapted for use in connection with such a flush plate as above described and has unusual advantages when used with such a plate. Flush plates are ordinarily of high finish, and it is practically impossible to secure indications through a sight opening in the plate without disfigurement. Furthermore, there is the objection of not 120 having a dust-tight structure where such sight openings are used.

125. Obviously the various details of the device might be varied and modified without departing from the spirit or intent of the 130

invention, and the indications as heretofore stated might be made in various ways, by different colors, by different words or by a combination of colors and words. Furthermore, the surface of the indicating plate corresponding to one position may be roughened, while the balance is left smooth. When so roughened, it is obvious that the sense of touch, by placing the finger over the sight opening, will readily distinguish the position of the indicator and the corresponding position of the switch parts.

What I claim as my invention and desire to secure by Letters Patent is:—

15 1. A switch handle provided with means of attachment to a switch mechanism and inclosing a movable indicator for indicating the position of the switch parts, and operative connections for moving said indicator upon movement of the switch parts.

20 2. A switch handle having means of attachment to a switch mechanism and inclosing an automatically actuated indicator and interengaging mechanical connections intermediate the switch mechanism and indicator for moving said indicator upon changes of position of the switch mechanism.

25 3. A switch handle provided with means of attachment to a switch mechanism and provided with a movable indicator borne within and inclosed by the button, and automatic means for moving said indicator upon predetermined movements of the button and switch mechanism.

30 4. A switch handle having means of attachment to a switch mechanism and provided with an interiorly arranged pivoted indicator, and means intermediate said pivoted indicator and switch mechanism for controlling the movements and position of the indicator.

35 5. A switch handle provided with a housing having means of attachment to the switch mechanism, an indicator lever pivoted within said housing, and operative connections intermediate said pivoted indicator lever and switch mechanism for controlling the movements of the former dependent upon the position of the latter.

40 6. A switch handle having a housing provided with means of attachment to a switch mechanism, a pivoted indicator member mounted in said housing, an actuating member operatively connected therewith and dependent therefrom, an actuating ring operatively mounted to move said actuating member and indicator, and means coöperating

therewith for moving said parts upon a rotation of the handle and switch mechanism.

45 7. A switch handle having a sight opening therein, a movable indicator mounted within the handle and visible through said sight opening, means for connecting said handle with a switch mechanism, and automatic means for moving the indicator dependent upon the movement of the switch mechanism.

50 8. A switch handle inclosing a housing, said housing providing a means of attachment to a switch mechanism, an indicator operatively mounted in said housing, and operative connections extending beyond said housing for controlling the position of the indicator dependent upon the movement of the switch mechanism.

55 9. A switch handle inclosing a housing, said housing formed from sheet metal bent to shape, and providing a means of attachment to a switch mechanism, an indicator operatively mounted in said housing, and operative connections extending beyond said housing for controlling the position of the indicator dependent upon the movement of the switch mechanism.

60 10. A switch handle having an interior chamber and a sight opening connecting therewith, a movable indicator operatively mounted within said chamber and with reference to said sight opening, and means for automatically moving said indicator.

65 11. In combination with a switch mechanism, a switch handle having means of attachment thereto, an indicator pivoted within the switch handle, an actuating yoke connected therewith, an actuating ring appurtenant to said yoke and operatively connected with the switch mechanism to rotate therewith, a cover for said switch mechanism, and means appurtenant to said cover for moving the actuating ring and indicator 70 mechanism upon rotation of the switch parts.

75 12. A switch handle provided with means of removable attachment to a switch mechanism and inclosing a movable indicator for indicating the position of the switch parts, and means appurtenant to said handle for connecting said indicator with the switch mechanism upon application of the handle to said mechanism.
